UNITED STATES PATENT OFFICE.

FRANK G. DRESSE, OF PROVIDENCE, RHODE ISLAND.

DENTAL FLOSS DISPENSER.

Application filed November 25, 1922. Serial No. 603,239.

To all whom it may concern:

Be it known that I, FRANK G. DRESSER, a citizen of the United States, residing at Providence, in the county of Providence and State of Rhode Island, have invented 5 certain new and useful Improvements in Dental Floss Dispensers, of which the following is a specification.

This invention relates to devices for holding and dispensing dental floss. A great variety of articles of this character have been devised heretofore, but those of which I have been able to learn apparently have been constructed with the sole idea of reducing the manufacturing cost to the lowest degree possible. The result is that they are very unsatisfactory to use. They are particularly objectionable in that the dental floss breaks inside the container or casing 15 very frequently, thus making it necessary to open the casing and unsnarl or unwind a length of the floss.

The present invention aims to devise a dental floss dispenser which, while capable 20 of being manufactured economically, will be of substantial construction, will be convenient to use, and will be entirely reliable in operation.

The nature of the invention will be readily 25 understood from the following description when read in connection with the accompanying drawings, and the novel features will be particularly pointed out in the appended claims.

Referring now to the drawings,

Figure 1 is an exploded perspective view 30 of a device embodying the invention in the form at present preferred;

Fig. 2 is a perspective view of the device 35 when assembled and ready to use;

Fig. 3 is a vertical cross sectional view of the device shown in Fig. 2; and

Fig. 4 is a cross sectional view through 40 the cutter with which the device is equipped.

The dispensing device shown comprises a case consisting of two parts, designated at 45 2 and 3, respectively, each part consisting of a circular disk-shaped end with a peripheral flange extending therefrom. These two flanges are designed to telescope one within the other, as clearly shown in the drawings;

and the flange of the part 3 carries two pins, one of which is shown at 4, which are designed to engage with the walls of angular slots 5-5 in the part 2 to form a bayonet 50

joint connection securing these parts together.

The supply of dental floss F is wound on a reel 6 which is rotatably supported on a pin 7 fixed in the part 3. It is desirable to 60 prevent this reel from rotating too freely as the floss is unwound from it, and for this purpose the reel has a central recess 8 formed therein, and a coiled spring 9 secured to the part 2 by a screw 10 bears on the bottom of the recess 8. It will be noted 65 that the part 3 of the case has a central enlargement 12 against which the reel is pressed by the spring 9, but that the reel does not touch the part 3 at any other point. 70 Consequently, the braking action produced by the spring 9 is confined to the central portion of the reel and variations in the friction exerted on the reel, therefore, do not produce nearly as great variations in total 75 resistance to the rotation of the reel as would be produced if the frictional drag were applied at points nearer the periphery of the reel. In other words, this arrangement produces a substantially constant frictional resistance to the rotation of the reel. 80

The flange of the part 3 has a slot 14 formed therein through which the strand of floss is drawn when the case is closed. For the purpose of facilitating the cutting off or 85 breaking of the strand when the desired length has been drawn from the reel, the case is provided with a cutter, the construction of which is best shown in Fig. 4. This cutter comprises a knife or blade 15, preferably consisting of a small stud of tool steel set into the cover 3, the lower end of this stud being circular in cross section so that it will fit into a hole drilled in the cover. The outer end is reduced to fit in a slot formed 90 in a short bar 16 which is secured to the cover by a screw 17 but is held away from the cover by a spacing collar 18. A knife edge is formed on the part 15 in the space exposed between the parts 3 and 16. A 100 serviceable cutter thus is provided, the blade of which can readily be removed and replaced by a new one or sharpened whenever desired.

In loading the device a reel filled with 105 floss is placed on the stud 7, and the flange of the casing member 3 is then telescoped within the flange of the opposite member 2 and given a partial rotation to lock the pins 4 within the slots 5. This operation prop- 110

erly seats the spring 9 within the recess 8 in the reel. It will be observed that the portions of the slot 5 within which the pins 4 rest at this time are slightly curved or depressed to receive the pins, and that the spring 9, due to its tendency to force the parts 2 and 3 away from each other, tends to hold the pins in these portions of the slots, and therefore resists the relative 10 movement of the parts 2 and 3 which is necessary in order to unlock them for the purpose of opening the case. While the parts are being assembled in the manner just described, the strand of floss should be 15 drawn through the slot 14.

When it is desired to use a piece of floss the desired length is drawn off and pulled across the cutter, as clearly shown in Fig. 2. A slight pull severs the floss leaving an end 20 still projecting from the case. The braking action exerted on the reel by the spring 9 is sufficient to keep it from rotating too freely, but is not great enough to cause any danger of breaking the floss as it is drawn from the 25 casing. Consequently, there is no danger of the floss becoming broken or snarled inside the casing.

While the device has been herein shown as made of unusually heavy parts, such as 30 would be turned out on a lathe or by automatic screw machinery, it will be appreciated that an article sufficiently sturdy and substantial for most purposes can be made by the punch and die process, only minor 35 modifications in the structure shown being necessary for this purpose. It can also be made from celluloid or the like.

Having thus described my invention, what I desire to claim as new is:

40 1. A dental floss dispenser comprising a closed case consisting of two telescoping parts having a bayonet joint connection with each other, a reel enclosed in said case and adapted to hold a supply of dental floss, said reel being centrally recessed, and a coiled spring carried by one of said casing parts and bearing on the bottom of said recess.

45 2. A dental floss dispenser comprising a closed case consisting of two parts, each part including a circular disk-shaped end

portion with a peripheral flange extending therefrom, said flanges telescoping with each other and having cooperating parts to secure them together, a pin projecting inwardly from the central portion of one of said disks, a reel rotatably mounted on said pin and having a recess in one face thereof, said reel being adapted to hold a supply of dental floss, and a coiled spring carried by 55 one of said casing members and bearing on the bottom of said recess, one of said casing members having a slot therein through which the dental floss wound on said reel 60 may be drawn.

3. A dental floss dispenser comprising a closed case consisting of two parts, each part including a circular disk-shaped end portion with a peripheral flange extending therefrom, said flanges being constructed to 70 telescope with each other and having cooperating parts to secure them together, a pin projecting inwardly from the central portion of one of said disks, a boss formed on said disk adjacent to said pin, a reel rotatably mounted on said pin and bearing against said boss, said reel being adapted to hold a supply of dental floss and having a recess in the face thereof opposite the boss 75 on one of said casing members, and a coiled spring carried by the opposite casing member and arranged to bear on the bottom of said recess.

4. A dental floss dispenser comprising a closed case consisting of two parts, each 80 part including a circular disk-shaped end portion with a peripheral flange extending therefrom, said flanges being constructed to telescope with each other and having cooperating parts to secure them together, a reel 85 mounted to rotate in said case and adapted to hold a supply of dental floss, means for resisting the free rotation of said reel, one of the parts of said case having a slot therein through which the dental floss may be 90 drawn, a blade 15 seated in the disk of one of said casing parts, a bar 16 bearing on the outer end of said blade, and a screw 17 for securing said bar to the casing member and clamping said bar on said blade.

FRANK G. DRESSER.
